DESIGN FOR A CIGARETTE DISPENSER OR THE LIKE

O. Neil Christensen, Oak Park, Ill., assignor to John B. Whitted, Glencoe, Ill.

Application April 18, 1938, Serial No. 76,581

Term of patent 7 years

To all whom it may concern:

Be it known that I, O. Neil Christensen, a citizen of the United States, residing at Oak Park, in the county of Cook and State of Illinois, have invented a new, original, and ornamental Design for a Cigarette Dispenser or the like, of which the following is a specification, reference being had to the accompanying drawing forming a part thereof.

The figure is a perspective view of a cigarette dispenser showing my new design. The right-hand side, which is not shown, is identical with the left-hand side which is shown.

I claim:

The ornamental design for a cigarette dispenser or the like, as shown and described.

O. NEIL CHRISTENSEN.
